UNITED STATES PATENT OFFICE.

WILLIAM B. CHOATE, OF AURORA, ILLINOIS.

PIPE THIMBLE OR INSULATOR.

SPECIFICATION forming part of Letters Patent No. 693,234, dated February 11, 1902.

Application filed May 14, 1900. Serial No. 16,641. (No model.)

To all whom it may concern:

Be it known that I, WILLIAM B. CHOATE, of Aurora, in the county of Kane, and in the State of Illinois, have invented certain new and useful Improvements in Pipe Thimbles or Insulators; and I do hereby declare that the following is a full, clear, and exact description thereof, reference being had to the accompanying drawings, in which—

10 Figure 1 is a sectional view of the outer sleeve of my thimble or insulator. Fig. 2 is a partial sectional view of the inner sleeve thereof. Fig. 3 is an elevation of my thimble, having its sleeves in operative relation; 15 and Fig. 4 is a sectional view taken on the line $\alpha\alpha$ of Fig. 3.

The object of my invention is to provide a thimble or insulator for protecting floors or partitions from injury by the heat of steam, 20 water, hot-air, and other heated pipes which pass therethrough, such insulator having the qualities of providing an air-space between such pipe and the floor or partition through which it passes, said air-space permitting free 25 passage of air therethrough and preventing contact between the hot pipe and the floor or partition, of being readily adjusted to the thickness of such floor or partition, and of having its parts so firmly fastened together 30 that they shall not be displaced accidentally or by the jarring of the pipe or building; and to such end my invention consists in the thimble or insulator for steam, water, hot-air, and other heated pipes, substantially as herein- 35 after specified.

In carrying my invention into practice I provide inner and outer sleeves A and B, respectively. The inner sleeve A consists of a body C, formed of a sheet bent into cylindrical form 40 and having its meeting edges united in the usual manner, an inturned lip D being formed on one end of such body, and an annular flange E larger in diameter than the body, said flange E being attached to the body by 45 having its inner edge turned over such lip D. A spring-lug F projects through a slot G, extending longitudinally in the side of the body C, such lug being preferably formed by doubling upon itself the end of a wire H, whose opposite end is attached to the body by being 50 passed through two openings I and I in the

material thereof. The spring of the wire H tends to hold the lug at the end of the slot nearest to the flange E, the lug thus being capable of yielding in a direction away from 55 such flange.

The outer sleeve B consists of a cylindrical body K, having a flange L attached thereto in a manner similar to that used in connecting the flange E to the inner sleeve. The body 60 K preferably consists of a sheet M, having spiral ribs N and N formed on the inner surface thereof, such ribs being conveniently formed by crimping the material of such sheet. The edges opposite the sheet M are 65 conveniently connected by a strip O, having its edges bent inward and interlocked with the outturned edges of the sheet M. The spiral ribs are interrupted along the strip O, so that each rib passes but part way around 70 the body B, and a free passage is formed across such ribs and along such strip. The ends of the spiral ribs are preferably not in line with each other, but are staggered, so that each end on one side of the free passage 75 is substantially opposite the middle of the space between the nearest ends of such ribs on the opposite side of such space. The ribs thus form parts of two separate spirals, which are separated by half a pitch. Such ribs 80 might be made to form parts of three or more spirals.

In the operation of my device the outer sleeve is passed into the opening through the floor or partition until its flange abuts the adjacent surface thereof. The inner sleeve is inserted from the opposite side of such floor or partition until its flange abuts thereagainst. The spring-lug F traverses the passage 85 through the ribs N and N until it is arrested by 90 contact of the flange E with the wall or partition. One of the sleeves is then turned, while the other is held stationary, the turning being in such direction that the spring-lug F will engage a rib N and draw the flanges firmly 95 against the opposite faces of the floor or partition, and the motion is continued until the lug has been made to yield to some extent. In case the lug should slip off the end of the rib it has engaged it will, owing to the staggering of the rib ends, be caught by the opposite end of the next higher rib and cause 100

the flanges to be drawn closer together until it has engaged a rib beyond which it cannot pass. The tension of the lug against the rib will prevent any accidental unfastening of the sleeves such as might otherwise be caused by the jarring of the house or of the pipe. The engagement of the sleeves of my thimble is thus effected by a simple thrust of the sleeves toward each other and a partial relative rotation, whereas with a continuous spiral rib it would be necessary to cause the lug to follow the entire course of the spiral until the flanges had reached their proper positions. The ribs separate the inner and outer sleeves, thus preventing contact of the hot pipe with the floor or partition and forming an insulating air-space. The interruption of the ribs provides a clear space for the direct passage of the air through the thimble.

Having thus described my invention, what I claim is—

1. A thimble for pipes consisting of an inner and an outer flanged sleeve, one of such sleeves having interrupted spiral ribs, and the other of such sleeves having a yielding lug that is adapted to engage with said ribs, substantially as and for the purpose described.

2. A thimble for pipes, consisting of an inner and an outer flanged sleeve, one of such sleeves having interrupted spiral ribs forming parts of a plurality of spirals, and the other of such sleeves having a lug that is

adapted to engage such ribs, substantially as and for the purpose described.

3. A thimble for pipes, consisting of an inner and an outer flanged sleeve, one of such sleeves having interrupted spiral ribs forming parts of a plurality of spirals, such interruptions being in line with each other, and the other of such sleeves having a lug that is adapted to engage such ribs, substantially as and for the purpose described.

4. A thimble for pipes, consisting of an inner and outer flanged sleeve, one of such sleeves having interrupted spiral ribs forming parts of a plurality of spirals, and the other of said sleeves having a spring-lug that is adapted to engage such ribs, substantially as and for the purpose described.

5. A thimble for pipes, consisting of an inner and an outer flanged sleeve, one of such sleeves having interrupted spiral ribs forming parts of a plurality of spirals, such interruptions being in line with each other, and the other of such sleeves having a spring-lug that is adapted to engage said ribs, substantially as and for the purpose described.

In testimony that I claim the foregoing I have hereunto set my hand this 10th day of May, 1900.

WILLIAM B. CHIOTATE.
